E. Holton.

Grist Mill.

Patented Apr. 3, 1835.

Att. 11

Apl. 3, 1835 391.

Elisha Holton
Sectored Patent

8739X

The Schedule referred to in these Sectored Patent and making part of the ^{same} containing a description in the words of the said Elisha Holton himself of his improvement in the construction of a Crust Mill.

To all to whom these presents shall come Be it known that I Elisha Holton of Westminster in the County of Windham and State of Vermont have invented a new and useful improvement in the construction of a Crust Mill and that the following is a full and exact description thereof reference being had to the annexed drawing of the frame of the Mill three feet and a half high by two and a half square and is made of timber three inches and a half square. B. is a movable sill the tenon on one end of which is placed into a long mortise in one of the posts in order thereby to raise and depress the spindle and runner by means of the bridge tree and box C. connected with it. D. is the floor supported by four rails one foot and six inches from the lower ends of the posts, two of these rails being six inches wide and each having a groove in its inner side in which another floor is supported. making a foundation for the bed stone; near the top of the posts, four other rails are framed in two of them supporting, a plank ten or twelve inches wide, one edge of which covers the center of the stones. On this plank eight inches from the screw A. a semicircular ring of cast iron is made fast, to receive in its notches the handle of the screw to keep it from turning. The hopper, shoe, curb, bridge tree, box, spindle, iron and balance beam, being arranged in the usual way. the stones should be one foot and eight inches in diameter. There follows a description

of my invention or improvement, for which a patent is desired to be secured. 1st The mode of pressing the runner down upon the bed stone, by means of turning down the screw a. which operates in a cast iron bolt box at the upper end of the damsel, and that upon the balance beam in the eye of the stone. 2nd The mode of raising the runner with the same screw and the levers and rods connecting it with the movable sill: The screw a. passes through the lever c. and is kept there by a collar made fast to it beneath the lever; this lever extends to a point directly above the end of the lever f. where they are connected by the rod g. which passes through them; the levers each bearing upon a shoulder at either end of the rod, the opposite end of the lever f. is connected with the movable sill by the rod h. which passes through the end of each the rod having a head on one end, and a screw nut on the other, each lever having its fulcrum at such distance from the point where the power is applied as will cause the box, spindle and runner to rise and lower as the screw is raised and lowered when turned which distance is one third the length of the lever. The size and proportions of the whole may be varied to suit the views and purposes of the constructor. —

Operation any of the forces usually made use of to propel machinery may by means of a belt passing over the pulley above the box be applied to put the runner in motion. after the grain is put into the hopper the runner should be caused to grind to the required fineness by turning the screw above the damsel. (Done this 23rd day of March 1835. at Westminster U. S.)
